(57) **CLAIM**

The ornamental design for a 360 degree display case, as shown and described.

DESCRIPTION

This product is used to enclose and display any object that fits inside the physical limitations of the display. The visible assembly consists of; a transparent cover, a rotating display wheel, a base, and a body. The body is the support for the transparent cover, rotating display wheel, and the cover for the base.

FIG. 1) is a perspective view of a 360 degree display case showing the new design

FIG. 2) is a front view thereof.

FIG. 3) is a right view thereof.

FIG. 4) is a back view thereof.

FIG. 5) is a left view thereof; and,

FIG. 6) is a top view thereof.

The bottom is flat and unornamented.

The 360 degree display case has a top and 4 sides that are transparent.
